UNITED STATES PATENT OFFICE

CLARKSON A. DISBROW, OF NEW ROCHELLE, NEW YORK, ASSIGNOR TO THE RAIL JOINT COMPANY, OF NEW YORK, N. Y., A CORPORATION OF NEW YORK

SPLICING STRUCTURE FOR DIFFERENT TYPE RAILS

Application filed August 2, 1929. Serial No. 382,877.

This invention relates to rail joints, and has particular reference to the splicing of rails of the so-called headfree type with standard rails.

In track construction, as the advantages of the so-called headfree rail disclosed and claimed in Thomson Patents Reissue No. 15,773 and No. 1,507,870 have become more fully understood and appreciated, it has developed that such rails are coming into general use, with the result that rails of the head-free type are being incorporated in track with both worn and unworn standard rails. This means, of course, that where a headfree rail is inserted in a track contiguous to standard rails, a satisfactory splice must be effected between the standard rail and the headfree rail.

Primarily, a headfree rail is so designated because the joint bar used therewith has head clearance from the underside of the rail head and a loading engagement at the head fillet of the rail. According to this construction, tightening of the joint bolts results in an upward and outward sliding engagement of the joint bar with the head fillet of the rail until the bar is drawn solidly into proper fit with the rail. On the other hand, the joint bar commonly used with standard rails has head contact with the fishing surface at the underside of the rail head and with the upper side of the rail flange, and when the joint bolts are tightened the bar is or should be, drawn in a straight line laterally toward the rail web; otherwise any canting of the bar would result in an improper fit of the bar with the rail, with danger of fracture or breakage of the bar either by tightening of the bolts or when the joint is subjected to load.

With the development consisting in replacing standard rails by headfree rails has come the problem of providing a splice answering particularly to the requirements of strength between rails of these two different types. To solve this problem, it has been proposed to provide a joint bar formed at one end for rail-head clearance and loading engagement with the head fillet of the head-free rail, and at its other end formed for head

contact with the under face of the head and with the upper face of the rail flange of the standard rail. Inasmuch, however, as proper fit of a head contact bar with a rail can be accomplished only by drawing the bar laterally in a straight line into engagement with the rail, and proper fit of a headfree bar with a rail is effected by drawing the bar so that it has upward and outward sliding contact with the head fillet of the bar and a rotative movement of its foot, it is manifest that a joint bar having at one end a headfree construction and at its other end a head contact construction would be subjected by the joint bolts to twisting strains, and that proper engagement of either end of the bar with either rail would be practically impossible. Moreover, such a bar could not be satisfactorily rolled, and if formed in any manner and embodied in a track, would be extremely susceptible to fracture or breakage, especially when subjected to load. Accordingly, the purpose of the present invention is to provide a joint between a so-called headfree rail and a standard rail meeting fully the requirements of strength, etc., and avoiding bolt imposed or other strains on the joint bar such as might be likely to cause fracture or breakage of the joint upon load being imposed thereon.

In solving the problem presented by the aforesaid development, and in carrying out the foregoing purpose, it is proposed, according to this invention, to provide a joint bar having its respective rail engaging end portions vertically and laterally offset with respect to one another to compensate for any difference in the height and section of the rails, and to form each end of the bar for head-clearance and head fillet loading engagement with its related rail, whereby the same movement of all portions of the bar is effective to secure a desired fit of the bar with each rail, and whereby imposition of undesirable strains in the joint are avoided. The present bar thus may be rolled and economically forged or bulldozed to the final form desired.

In the accompanying drawings, which are illustrative of the invention, and wherein like

characters of reference denote corresponding parts in the different views:—

Fig. 1 is a side elevation illustrating a joint effected between a standard rail and a head-free rail in accordance with the present invention.

Figure 2 is a transverse section through the headfree rail end of the present joint.

Figure 3 is a transverse section through the standard rail end of the joint.

Figure 4 is a detail elevation of the medial portion of the inner face of the joint bar.

Figure 5 is a detail horizontal section on the line 5—5 of Fig. 1; and

Figure 6 is a view similar to Figs. 2 and 3 illustrating an incorrect type of rail joint between standard and headfree rails having certain disadvantages which the present joint eliminates.

Referring to the drawings in detail, R designates, generally, a standard rail, and R' a rail of the headfree type, the problem solved by this invention being to provide a practical, satisfactory joint between a pair of rails of these two different types.

Each rail is inclusive, as usual, of a head 10, a base 11 and a web 12, the essential difference between the standard rail R and the headfree rail R' being that the former is provided with a fishing surface 13 upon the underside of its head 10 adapted to be engaged by a complementary joint bar fishing surface, whereas the rail R' is or may be devoid of a fishing surface corresponding to the surface 13 of the rail R, loading engagement of a joint bar with a rail of this type essentially being with the head fillet 14 of the rail.

By reference to Fig. 6 of the drawings, wherein is illustrated the incorrect type of joint between a standard rail and a rail of the headfree type, it will be observed that the joint bar J has head fishing engagement with the under face 13 of the head of the standard rail shown in full lines, and head-free loading engagement with the head fillet 14 of the headfree rail shown in dotted lines.

As is well known in the art, the only practical way to secure proper fit of a head contact joint bar with a rail is by movement of the bar in a straight line inwardly and laterally toward the rail web, which may be accomplished by using ordinary care in tightening the joint bolts to draw the bar into operative fit with the rail. If this is not done and the bar is allowed to be drawn into engagement with the rail in a canted position, strains are set up which may result in fracture or breakage of the bar immediately same is subjected to load, if fracture or breakage does not result from tightening of the bolts. Moreover, unless the bar is drawn by the joint bolts so that its fishing surfaces are disposed flatly against the fishing surfaces of the rail, a satisfactory joint bearing

is not produced irrespective of the liability of fracture or breakage of the bar.

As distinguished from the movement necessary to be imparted to a head contact bar to secure a proper fit of such a bar with a rail, a headfree joint bar is adapted to be drawn into engagement with a rail by a combined lateral and rotary movement, the head of the bar initially being engaged with the web of the rail and being adapted to ride upwardly and outwardly under the influence of the force exerted thereon by the joint bolts, and the blows of a maul or the like, until the head of the bar takes loading engagement with the head fillet of the rail, all as fully set forth in the aforesaid Thomson patents and as indicated herein by the showing in Fig. 6 of the drawing.

From the foregoing the impracticability of a joint bar formed at one end for head contact with a standard rail, and formed at its other end for headfree, loading engagement with the head fillet of either a standard or a headfree rail, is at once apparent. If the headfree end of the bar is drawn into engagement with the rail in the proper manner, obviously the head contact end of the bar will be canted, rendering it impossible, because of the inherent rigidity of the bar, to draw the head contact end of the bar properly into engagement with the rail, and if the attempt is made to do so, twisting strains will be set up in the bar rendering it extremely likely to fracture or breakage when subjected to load. On the other hand, if the head contact end of the bar is drawn in a straight line laterally to secure proper fit of this end of the bar with its related rail the headfree end will be held against upward and outward movement with consequent improper fit of this end of the bar with its rail, and if it is attempted to draw both ends of the bar into engagement with the rails simultaneously the same impracticable, undesired results will follow.

According to the present invention, the joint bar J is formed head free throughout its length, its ends being vertically and laterally offset with respect to one another to compensate for any difference which may exist in the height and section between the respective rails. With such a bar, the same movement of each end thereof is effective to secure proper fit of each end with the rail, the movement of the bar into operative engagement with each rail, being upwardly and outwardly in the manner previously stated. This obviously avoids any twisting or oppositely directed strains being set up in the bar when the joint bolts are tightened and results in a joint between a standard and a headfree rail which possesses all of the advantages with respect to the standard rail as are inherent with respect to the headfree rail.

An additional important feature of the

present invention resides in forming the rounded, rail head fillet engaging portion of the head of the bar with a medial depression, X, so that contact of the head of the bar with the extreme end portions of the rails is avoided. This has the advantage that when the ends of the bar are vertically and laterally offset to compensate for any difference in height and section between the rails, any interference of the deflected or distorted medial portion of the bar with a proper fit of the head of the bar with the head fillets of the rails is eliminated. It also has the further advantage of avoiding marring or chipping of the head loading engagement portions of the bar by the ends of the rails, due to the pound of wheels passing over the joint.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:—

1. In a rail joint, a standard rail, a head-free rail, and a joint bar connecting said rails having head clearance from the underside of the head of the standard rail and loading engagement at the head fillet of each rail.

2. In a rail joint, a standard rail, a head-free rail, and a joint bar connecting said rails, each end of said joint bar being of the same cross sectional design and having head clearance from the underside of the head of the rail and loading engagement at the head fillet of the rail.

3. A joint bar for connecting a standard rail with a headfree rail, the ends of said bar being vertically and laterally offset with respect to one another to compensate for a difference in height and section between the rails, and each end of said bar being formed to have head clearance from the underside of the head of the rail and loading engagement with the head fillet of the rail.

4. A compromise joint bar for connecting a standard rail with a headfree rail, the head of said bar being formed at each end thereof for clearance from the underside of the head of the rail and for loading engagement with the head fillet of the rail, the fillet engaging surface of the head of said bar being medially recessed.

5. A rail splicing structure including in combination a standard type rail with head fishing surfaces, another type rail with no head fishing surfaces and a joint bar having at its upper inner corner a bearing member adapted to have rail engaging and loading engagement in the head fillets of both types of rail.

6. A rail splicing structure including in

combination a standard type rail with flat head fishing surfaces and another type rail whose head has bottom corner truncations eliminating flat head fishing surfaces, and a joint bar provided at its upper inner corner with a rounded bearing member having loading engagement in and against the head fillets of both rails and also having an inward and upward sliding adjustment over the rail flange.

7. A splicing structure for rail joints including in combination a standard type rail having flat head fishing surfaces and another type rail having no flat head fishing surfaces, and a joint bar having at its upper inner corner a rounded bearing member adapted to have a loading engagement in and against the head fillets of said both types of rails and also having a medial offsetting to compensate for any difference in height and section of the two rails.

In testimony whereof I hereunto affix my signature.

CLARKSON A. DISBROW.
